(57) **CLAIM**

The ornamental design for an anti barking device set as shown and described.

DESCRIPTION

FIG. 1 is a front, right, top perspective view of an anti barking device set, with the first component shown in isolation for clarity of disclosure;

FIG. 2 is a back, right, top perspective view of the first component;

FIG. 3 is a front view of the first component;

FIG. 4 is a back view of the first component;

FIG. 5 is a left view of the first component;

FIG. 6 is a right view of the first component;

FIG. 7 is a top view of the first component;

FIG. 8 is a bottom view of the first component;

FIG. 9 is a front, right, bottom perspective view of an anti barking device set, with the second component shown in isolation for clarity of disclosure;

FIG. 10 is a back, left, top perspective view of the second component;

FIG. 11 is a front view of the second component;

FIG. 12 is a back view of the second component;

FIG. 13 is a left view of the second component;

FIG. 14 is a right view of the second component;

FIG. 15 is a top view of the second component;

FIG. 16 is a bottom view of the second component; and,

FIG. 17 is an enlarged view of encircled area 17 shown in FIG. 8.

The broken lines shown on the drawings depict portions of the anti barking device set that form no part of the claimed design. The dot dashed lines in FIG. 8 and FIG. 17 depict boundaries of the enlarged views and form no part of the claimed design. The claimed design is an anti barking device set that is comprised of the first component and the second component.
